UNITED STATES PATENT OFFICE.

CHARLES WEINBERG, OF NEW YORK, N. Y., ASSIGNOR TO C. WEINBERG & CO., OF SAME PLACE.

DESIGN FOR GALLOON.

SPECIFICATION forming part of Design No. 21,516, dated May 3, 1892.

Application filed March 18, 1892. Serial No. 425,480. Term of patent 7 years.

To all whom it may concern:

Be it known that I, CHARLES WEINBERG, a citizen of the United States, residing in the city and State of New York, have invented a new Design for a Galloon, of which the following is a specification.

This design relates to the ornamental appearance of the pattern upon the surface of the galloon.

10 The leading features of this design consist in a checkered ornament running longitudinally of the gimp, with stripes at each side thereof, with raised figures similar to braiding, and transverse ribs dividing the pattern up 15 longitudinally into sections. The design of the braid or galloon is represented in the accom-

panying drawing upon an enlarged scale. The transverse ribs *a* divide the pattern up into sections, and the longitudinal central ornament has a checkered appearance, as at *b c*, 20 and the groups of raised figures at *d* have a braided appearance and the edge of the gimp is scalloped.

What I claim is—

The design for a galloon, substantially as 25 shown and described.

Signed by me this 15th day of March, 1892.

CHARLES WEINBERG.
